UNITED STATES PATENT OFFICE.

MAUDIE HANEY, OF QUINTON, ARKANSAS.

SWILL-CAN.

No. 926,325.

Specification of Letters Patent.

Patented June 29, 1909.

Application filed July 16, 1908. Serial No. 443,906.

To all whom it may concern:

Be it known that I, MAUDIE HANEY, a citizen of the United States, residing at Quinton, in the county of White and State of Arkansas, 5 have invented certain new and useful Improvements in Swill-Cans, of which the following is a specification.

This invention relates to a receptacle, having special reference to a receptacle which is 10 especially adapted to contain garbage.

An object of this invention is to provide a receptacle of this character which is practically hermetically sealed at all times to prevent the escape of disagreeable odors.

15 A further object of this invention is the provision of a device of this character with a means whereby the lid may be raised by the operation of the foot so that the hands may be free in order to pour the waste into the receptacle when opened.

20 A further object of this invention is the provision of an auxiliary opening whereby small particles of vegetable matter may be inserted in the can without opening the top 25 thereof.

Other objects and advantages will be apparent from the following description and it will be understood that changes in the specific structure shown and described may be 30 made within the scope of the claims without departing from the spirit of the invention.

In the drawings forming a portion of this specification, and in which like numerals of reference indicate similar parts in the several 35 views, Figure 1 is a side elevation of the complete receptacle, Fig. 2 is a top plan view of the same, Fig. 3 is a front elevation showing the auxiliary opening of the receptacle, Fig. 4 is a vertical cross section of the complete 40 device.

Referring now to the drawings 10 designates a receptacle which is preferably cylindrical and which is provided intermediately of one of its sides with a diagonally upwardly 45 extending spout 11 of a reasonably large diameter. The upper end of the spout 11 is provided with a lid 12 which comprises a strip of metal circularly formed as shown at 13 which fits into the end of the spout 11 and 50 carries upon its outer edge a disk 14 which fits over and extends beyond the upper edge of the spout 11. A suitable handle 15 is disposed upon the outer face of the disk 14 for the purpose of withdrawing the lid 12 from

the spout 11. The receptacle 10 is provided 55 with a cover 16 upon its upper open end which is hinged as at 17 to the top edge thereof. The back of the receptacle 10 carries a metal plate 18 which is extended beyond the upper extremity of the receptacle 10 and is 60 provided with a groove 19 through which is adapted to pass a cable 20 which extends forwardly and downwardly to the central portion of the cover 16 where it is secured in an eye 21 carried upon the upper face of the 65 cover 16. The cable 20 extends downwardly back of the receptacle 10 where it is secured to the outer extremity of a foot lever 22 fastened to the receptacle 10. The foot lever 22 is hingedly supported upon a metallic strip which is riveted to the rear side of the receptacle 10 and admits of the extension of the lever 22 rearwardly therefrom.

In use, the operation of the device is as follows: When it is desired to deposit vegetable matter or small particles of waste matter of like character the cover 12 is withdrawn from the spout 11 and the waste is deposited therein. The spout 11 is disposed at such an angle that it renders it more easy 75 of access than the opening in the top of a can of ordinary construction. If a large quantity of large pieces of refuse are deposited in the receptacle 10 the foot lever 22 is depressed and the cover 16 is raised through 80 the action of the cable 20. As soon as the matter is deposited in the receptacle 10 the cover 16 will return to its normal closed position by its own weight.

What is claimed is:—

1. A device of the character described comprising a receptacle, an upwardly and diagonally disposed spout upon one side of said receptacle, a cover for said spout, a hinged cover for said receptacle, a metallic plate secured at the back of said receptacle extending upwardly beyond the upper edge of said receptacle, a cable secured to the central portion of the cover and passed over said metallic plate and a foot lever disposed on the rear side of said receptacle near the bottom thereof to support the extremity of said cable.

2. In a device of the character described, the combination of a receptacle, a spout upwardly extended from one side of said receptacle, a cover detachably positioned upon the outer extremity of said spout, a hinged cover carried by said receptacle, a metallic

plate disposed at the back of said receptacle and extended upwardly beyond said cover, a cable secured to the central portion of said cover and extended backwardly over the upper edge of said plate and a foot lever hingedly disposed upon the rear side of said receptacle adjacent the bottom thereof, the opposite extremity of said cable secured to

the outer end of said lever for raising said cover at times. 10

In testimony whereof I affix my signature, in presence of two witnesses.

MAUDIE HANEY.
